US0D1056211S

(12) **United States Design Patent** (10) **Patent No.:** **US D1,056,211 S**
(45) **Date of Patent:** **** Dec. 31, 2024**

(54) **RADIOACTIVE THERAPEUTIC DEVICE**

(71) Applicants: **David E. Wazer**, Westwood, MA (US);
Thomas A. DiPetrillo, Dover, MA (US); **John J. Munro, III**, North Andover, MA (US)

(72) Inventors: **David E. Wazer**, Westwood, MA (US);
Thomas A. DiPetrillo, Dover, MA (US); **John J. Munro, III**, North Andover, MA (US)

(73) Assignee: **PointSource Technologies, LLC**, Boston, MA (US)

(**) Term: **15 Years**

(21) Appl. No.: **29/937,380**

(22) Filed: **Apr. 15, 2024**

Related U.S. Application Data

(63) Continuation of application No. 17/544,174, filed on Dec. 7, 2021, now Pat. No. 11,957,932, which is a continuation of application No. 16/688,392, filed on Nov. 19, 2019, now Pat. No. 11,224,761.

CLAIM

The ornamental design for a radioactive therapeutic device, as shown.

DESCRIPTION

FIG. 1 is a perspective view of a radioactive therapeutic device;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

1 Claim, 4 Drawing Sheets
